UNITED STATES PATENT OFFICE.

HERBERT G. BEEDE, OF PAWTUCKET, RHODE ISLAND.

THREAD-GUIDE FOR THREAD-BOARDS OF TWISTING OR SPINNING MACHINES.

1,075,184.

Specification of Letters Patent.

Patented Oct. 7, 1913.

Application filed November 6, 1912. Serial No. 729,775.

To all whom it may concern:

Be it known that I, HERBERT G. BEEDE, a citizen of the United States, residing at Pawtucket, in the county of Providence and State of Rhode Island, have invented certain new and useful Improvements in Thread-Guides for Thread-Boards of Twisting or Spinning Machines, of which the following is a specification.

10 My invention relates to a thread guide for the thread board of a twisting or spinning machine, and my invention consists in an improved construction of the thread guide, as will be hereinafter described.

15 It has been customary heretofore to have for the thread guide on the thread board, a glass or porcelain rod, in long lengths, with grooves therein at predetermined distances for the threads, and said rod attached to the 20 front edge of the thread board. In case of a thread cutting through said rod, or the rod becoming broken for any reason, it has been necessary to substitute a new rod of the same length as the old rod, which means 25 considerable expense.

In my improved construction of the thread guide for the thread board, I make the thread guide in sections, preferably one section for each thread, and I preferably 30 connect these sections, and detachably secure them to the front edge of the thread board, by means of short metal tubes, or sections, secured to the front edge of the thread board by screws, or otherwise. The sections of 35 the thread guide are preferably made solid, of porcelain or glass, and they extend into the ends of the connecting sections, as will be hereinafter fully described.

Referring to the drawing:—Figure 1 is a 40 plan view, and partial section of a thread board, and my improved thread guide attached to the front edge thereof. Fig. 2 is a front view of the parts shown in Fig. 1, looking in the direction of arrow *a*, same figure; the parts shown in section at the 45 right in Fig. 1, are shown in full lines in Fig. 2. Fig. 3 is a section, on line 3, 3, Fig. 2, looking in the direction of arrow *b*, same figure. Fig. 4 is a section, on line 4, 4, Fig. 50 2, looking in the direction of arrow *b*, same figure.

In the accompanying drawing, 1 is a detached section of a thread board of ordinary construction, having its front edge recessed, 55 as shown in Figs. 3 and 4, to receive the thread guide. The thread guide of my im-

proved construction consists of a series of short sections 2, of glass, porcelain, or other suitable material, preferably made solid, and with a peripheral groove or recess 2' therein, 60 preferably at equal distances from each end, which acts as a groove to guide and direct the thread. In connection with the thread guide sections 2, a series of sections 3, preferably of tubular metal, are used; each end of the tubular sections 3 are preferably recessed to receive the ends of the thread guide sections 2, as shown in sectional view at the right in Fig. 1. Each section 3 is secured to the front edge of the thread board, in this 65 instance by a screw 4, passing through the tubular section 3, and screwed into the front edge of the thread board 1, as shown in Figs. 1 and 3. The holding tubular sections 3 act to detachably hold in position and secure to 70 the front edge of the thread board 1, the thread guide sections 2. Any number of thread guide sections 2 and holding sections 3 may be used, according to the length of the board. 75

In case of the cutting through of any one of the thread guide sections 2 by the passage of the thread thereover, or the breaking of any one of the thread guides 2, it is only necessary to remove said thread guide by 80 removing one or both of the holding sections 3, at each end of said thread guide, and then substitute a new thread guide, and replace the holding sections 3.

The advantages of my improvements may 85 be readily appreciated by those skilled in the art.

It will be understood that the details of construction of my improvements may be varied if desired, and the thread guide sections 2 may be made of any suitable material, and the thread guide holding sections 3 may also be made of any suitable material, and of hollow construction, or of solid construction with recessed ends, and an opening 95 therethrough for the attaching screw. In place of a single attaching screw, other attaching means may be employed for securing the holding sections 3 at the front edge 100 of the thread board. 105

Having thus described my invention, what I claim as new and desire to secure by Letters Patent is:

1. The combination with the front edge of a thread board, having a recess or groove 110 therein, of a series of thread guides extending along said edge in said recess, said

thread guides made separate, and of cylindrical shape in cross section, and having a peripheral groove or recess therein, and a series of attaching devices for said thread guides, to receive the ends of said guides, and detachably secure the same to the thread board.

2. The combination with a thread board, of thread guides, made in sections, and means for detachably securing said thread

guides to the thread board, said means comprising tubular sections to receive the ends of the thread guides, and means for securing said tubular sections to the thread board.

HERBERT G. BEEDE.
